UNITED STATES PATENT OFFICE.

IRRA KRUGER, OF ABERDEEN, SOUTH DAKOTA.

STEAM ICE-CUTTING DEVICE.

1,288,039.

Specification of Letters Patent. Patented Dec. 17, 1918.

Application filed September 30, 1918. Serial No. 256,345.

To all whom it may concern:

Be it known that I, IRA KRUGER, a citizen of the United States, residing at Aberdeen, in the county of Brown, in the State of 5 South Dakota, have invented a new, useful, and novel Steam Ice-Cutting Device to be Used in Ice-Houses for Cutting the Ice Instead of Using Saws for that Purpose.

The bottom and lower layers of ice in 10 large ice-houses are usually frozen solidly together thus necessitating the slow, difficult, and expensive process of hand-sawing so to separate the "cakes" or "blocks" of ice so they can be removed. This method in addition to being slow, difficult, and expensive is also very wasteful. In order to expedite 15 this process of separating the blocks of ice, and to conserve economy and prevent waste, I have invented a steaming device to be 20 used instead of a saw. Said device is illustrated in the accompanying drawings wherein similar letters refer to similar parts in the several figures, and wherein Figure 1 is 25 a vertical side-view of the entire device in the position of cutting a groove into a block of ice *w w.*

Fig. 2 is a vertical, longitudinal section through the steam-chamber or steam-tube. Fig. 3 is a vertical cross-section through the 30 steam-tube (a) along the dotted line 3—3 of Fig. 2, and Fig. 4 is a front view of the forward end of the steam-tube (a).

The dimensions shown in Figs. 2, 3 and 4 are substantially such as would be used in 35 the making of the device, though the form and size of the steam-tube (a), and the size and arrangement of the braces (f f), and of the handle (l), and of the steam-connections (s and t) are not of the essence of this invention and can be varied in size and design 40 to suit the conditions of use.

In Fig. 1 the steam ice-cutting or thawing tube is shown at (a). To the rear end thereof is suitably attached a steam pipe (t) 45 which is, in turn, suitably connected to a steam-hose (s) which connects with a steam boiler. A valve (v) is suitably placed on the steamline so the steam can be readily turned on or off by the operator. Suitable 50 braces (f f) are attached to the steam pipe (t) and to the steam-tube (a) to render the device rigid and to permit of its proper control by the operator from a handle (l).

In Fig. 2 (a) shows the steam-chamber or steam-tube within which is the steam-chamber (z). (This steam-tube may be of any suitable form or size or length but a cast metal tube of the form and size shown gives the best results.) At the rear end is a suitable connection (d) for the attachment of 55 the steam pipe (t) shown in Fig. 1. At the front end is a clean-out hole closed by a bolt (h) and a small vent-hole (i) through which a forward-operating steam jet (s') is expelled. Serially spaced along the bottom of the steam-tube (a) are a multiplicity 60 of projections or teeth (b) (preferably of triangular section as shown) which serve to hold the lower surface of the steam-tube (a) a little above the surface of the ice so 65 that the steam jets (s' s') can operate upon the ice most effectively. The rear surfaces of said projections (b) serve the purpose of scrapers to gather the sawdust (D) in the bottom of the groove and draw it therefrom 70 as the thawing device is drawn outwardly along the groove, thus cleaning the groove for the more rapid action of the steam upon the surface of the ice.

Through the bottom of the steam-tube (a) 80 and serially located between the projecting teeth (b) are a multiplicity of small holes (e e) which serve as vents or outlets for the steam in the chamber (z). These jets of live steam forced through these holes thaw 85 a channel or groove in the ice much more rapidly, and with much less expense, and with far less waste, than the ice could be cut with saws. On the top, and at each end of the steam-tube (a) may be formed bosses to 90 which the braces (f) may be fastened by the bolts (g).

I am aware that prior to my invention steam jets have been used in many connections for thawing purposes and I therefore make 95 no claim to that principle but only to its special application in the manner and by means of the device above described, namely, as a means of cutting ice in an ice-house in lieu of ice saws which have thus far been 100 used.

Having thus described my invention what I claim as new, novel, and useful, and on which I desire Letters Patent is,—

In an ice-cutting device the combination 105 of a hollow steam-tube or chamber suitably

braced and connected with a steam pipe through which steam is supplied to the tube; a multiplicity of projecting teeth, serially spaced along the bottom of the steam-tube, 5 to hold the tube above the surface of the ice and to serve as sawdust scrapers; and a multiplicity of holes through the bottom of

the steam-tube, serially spaced between the projecting teeth to serve as vents for the jets of steam from the steam-tube directed upon the surface of the ice for the purpose of cutting a groove in the ice by thawing the same, substantially as described.

IRA KRUGER.
